UNITED STATES PATENT OFFICE.

CHARLES VERNON BOYS, OF LONDON, ENGLAND.

CALORIMETER.

Application filed December 27, 1921. Serial No. 525,220.

To all whom it may concern:

Be it known that I, CHARLES VERNON Boys, F. R. S., a subject of the King of Great Britain and Ireland, and residing at 5 66 Victoria Street, Westminster, London, S. W. 1, England, have invented certain new and useful Improvements in Calorimeters, of which the following is a specification.

10 My invention relates to calorimeters, and although having special reference to the instrument described in my prior application Serial No. 440,453 is also applicable in part to non-recording and bomb calorimeters.

15 My invention consists in an improved construction of the operative thermometers, whereby the exposure of even a small portion of the liquid contents outside the circulating water is wholly avoided and in which 20 the lever system is carried by the metallic structure and neither directly nor indirectly by the lid of the calorimeter casing, thus avoiding small possible inequalities.

25 My invention consists also in the arrangement of the levers in planes mutually perpendicular, whereby the necessity for making the two thermometer bulbs of unequal capacity to compensate for the varying temperature of the inlet water as in my former 30 application is avoided.

Referring to the accompanying diagrammatic drawings:

Figure 1 is a vertical section on line 1—1 of Figure 2 through the calorimeter casing 35 and through the hot side of the calorimeter showing the cold side in elevation;

Figure 2 is a plan of the parts shown in Figure 1 with certain parts in section;

Figure 3 is a side elevation of the adjustable bell crank lever, of which

Figure 3^a is a detail;

Figure 4 is a vertical section showing a modified construction suitable for non-recording use, but with the upper part of the heat interchanger in elevation;

Figure 4^a is a sectional plan on the line 4^a—4^a of Figure 4.

Figure 5 is a sectional elevation of the air saturator taken on the line 5—5, Figure 1.

Parts or closely corresponding parts of my prior application mentioned above which appear are lettered with their original letters for ease of comparison, and the letters of like parts are the same in all the figures. 55

It will be apparent from the figures that the water delivered to the calorimeter at a known rate enters the pipe C₁ and so passes to the cold thermometer water vessel C₄, thence by the tube C₇ to the water ring C₈ 60 up through the interchanger B as shown on the right side in Figure 1 and Figure 4 and through the neck B₁ of the hot thermometer vessel C₅ and out by the tube C₂₇ to the air saturating box A₃ from which it 65

escapes by the pipe A₁₄ (Figure 5) either to a drain, or as I prefer through a radiator or pipe of extended surface where it acquires the temperature of the room to a tank to be pumped and used again. The gas measured and delivered at a known rate enters the burner tube C₂₁ and issuing therefrom burns producing the flame. The air for 70

combustion can only reach the combustion chamber C₁₅ by passing along the flat passage C₂₀ below the base C₁₄ of the calorimeter having come from the space around the cold thermometer vessel C₄ through the large hole B₂. The cold and hot thermometer spaces are separated by the partition 75 B₃. The way in which the air enters the cold thermometer space is the subject of one of the refinements of this specification and is described in connexion therewith.

The products of combustion descend 85 through the passages B₄ in the interchanger, as shown on its left side in Figure 1, and with any liquid condensed pass to the exit gas passage B₅ by way of the annular trough B₆.

90 The heat interchanger is made of sheet metal preferably of lead autogenously soldered for continuously recording calorimeters, but other metals such as copper or brass soft soldered might be used for instruments not in continuous use. Lead autogenously soldered is well known to resist the destructive action of the sulphurous vapours of burning gas and so is preferable more especially for continuous use. 95 100

It will be evident that other material than metal which can be made into sheets and joined and which is sufficiently heat conducting and incorrodible might be used 5 for the interchanger.

As will be seen from Figures 1 and 2, the heat interchanger is made of sheet metal bent or folded so as to contain numerous narrow up passages B_7 for the circulating 10 water and voluminous down passages B_4 for the gases of combustion.

In the horizontal section Figure 2, taken on the line 4—4 Figure 1, the metal of the heat interchanger B is shown as part of a 15 single strip of thin sheet metal bent backwards and forwards radially so as to enclose the narrow waterways B_7 between its own folds and between these and the casting C_5 . At the upper and lower ends of 20 said heat interchanger the radial waterways are somewhat widened as indicated in the figures so that there may be a sufficient water circulation up the inner folds of the metal. These inner folds are arranged to 25 be in contact or nearly so, in order that the ascending and descending gases may not intermix, and any accidental chinks left between these will in use be stopped by condensed water. Below the slight widenings of the radial waterways at the lower 30 end the folds are pinched together B_8 and soldered together and the outermost parts are bent inwards sufficiently for the interchanger to be driven into the ring C_9 and 35 soldered thereto so that water of circulation cannot escape below.

At the upper end of the interchanger the outermost parts are bent inwards B_9 and the radial webs are cut off at an angle as 40 shown in Figure 1, and there pinched together and soldered B_{10} , so that rising water can escape upwards and outwards in the numerous narrow passages B_7 between the bent-in portions. Three or more of these 45 radial portions are carried higher than the rest and being each made with a notch carry a flat dome of fused silica S or equivalent material which in use becomes hot enough to prevent water from condensing upon it, and as it is incorrodible, pimples of corroded metal immediately 50 above the flame cannot be formed. Where these hot gases impinge directly upon water cooled metal, condensation of water occurs and if the metal corrodes and forms a 55 pimple the condensed water drops upon the burner and puts out the flame.

Immediately above the silica dome a metal dome B_{12} is also provided and this is 60 soldered all round as shown at B_{13} to the bent-in portions aforesaid, and thus the hot gases are able to move outwards and downwards and the water is able to move upwards, but is not able to enter into the 65 passages for the gases. By this construc-

tion I am able to obtain a heat interchanger of great simplicity and cheapness of construction with a very large surface for the cooling of the gases so that it may be made compact and it is durable if made of lead. 70 A further advantage is the very small water content and the large cross-section of the down gas-ways. As will be seen at B_{14} , Figure 2, the ends of the strip of sheet metal are bent inwards into one of the down-gas passages and there soldered together. I have shown one form of bent sheet metal interchanger, but it is evident that such an interchanger having the special 75 features and advantages described may be 80 made in many forms and in two or more parts, but I claim all such constructions as equivalents.

The water after receiving its heat from 85 the interchanger passes through the small hole B_{15} in a neck B_1 of the hot water vessel C_5 where any differences of temperature of various streaks of water are eliminated by 90 mixing. From the neck the water passes through a number of holes B_{16} into the upper section where it passes in a thin sheet round the hot thermometer T_5 of improved 95 construction. The cold water entering the cold thermometer vessel C_4 is shown entering directly from the inlet pipe C_1 , and if as already mentioned this water has already 100 been brought to the temperature of the room this is permissible. If, however, the cold water entering the calorimeter is not brought to the temperature of the room the pipe C_1 should be carried round the cold water compartment before entering the cold thermometer vessel C_4 , so that the air for 105 combustion shall be brought to the temperature of the water as described in my said former application.

The operative thermometers according to 110 my present invention are of simplified construction and the hot and cold thermometers are identical in capacity and form, and they are made without connecting pipes and separate aneroid diaphragm boxes. As seen in vertical section in Figure 1, the hot water thermometer T_5 consists of a piece of tube T_7 of nearly the same diameter as the upper 115 section of the hot water vessel C_5 and the upper and lower ends are closed by corrugated aneroid discs B_{17} and B_{18} respectively, and the cold thermometer hidden within the cold thermometer vessel C_4 is identical. 120

To each of the lower corrugated covers B_{18} is soldered a conical support B_{19} designed to 125 rest in a conical central recess B_{20} to locate it accurately, while the upper ends have soldered to them spigot filling blocks B_{21} in which the screws T_{18} force the balls B_{22} into conical recesses B_{23} to seal in the liquid. For the reasons given in my former application, I prefer to employ amyl-alcohol for filling 130 these thermometers. Operative thermom-

eters of this simple construction are very easily filled by means simply of a capillary funnel, and then when apparently full a slight spinning of the conical point will bring any air bubbles to the centre where they can be ejected, liquid taking their place. They have the further advantage that they are wholly immersed in the water and the whole of the liquid in either thermometer is at the same temperature. The temperatures are indicated by the distances between defined axial points at the two ends of each thermometer. As the whole expansion is very small a most precise and powerful magnification system is essential and this can readily be made as shown in the drawings. Each thermometer carries a cap B_{24} screwed over the spigot block, and these caps carry axial points B_{25} B_{26} , preferably screw adjusted as shown, one acting upwardly on its lever B_{27} and the other downwardly on its lever B_{28} . As shown the hot bulb is the one with the downward action, but it is possible to arrange that the cold one has the downward action. Each axial point acts on the short end of its particular lever, and as will be seen from the drawing the levers have each the same magnification; in the example shown $2\frac{1}{3}$ to 1. The levers are carried on pillars B_{29} attached to the lid B_{30} of the hot water compartment which lid is definitely located. In the example shown the fulcrum axes are equidistant from the axis of the hot water compartment, but this while symmetrical and convenient is not essential. Both levers rest in notches at the upper ends of their respective pillars and the cold thermometer lever which is pushed up at each end as will be made clear, is held down on to its fulcrum B_{31} by the spring B_{32} . This construction is much more convenient than the use of overhead notches up against which the forces at the two ends would keep the lever engaged. The outer ends of the two levers terminate in the same transverse plane and the hot thermometer lever B_{28} carries a bell crank lever D working in a transverse vertical plane by a notch D_1 at one end of its short arm while the cold thermometer lever B_{27} presses down on the other end D_2 of its short arm and so overcomes a small backward pull applied to the end D_3 of the long arm vertically below. The short arm of this lever is made adjustable as to length by the screw D_4 , as is made clear in Figure 3.

It will be seen that with such a construction the backward or forward movement of the lower end D_3 of the bell crank lever is determined only by the difference of temperature of the two operative thermometers for any change of temperature common to the two merely raises or depresses the bell crank lever as a whole by a very small amount. The small backward force constantly applied to the lower end of the bell

crank lever is transmitted through the link D_5 from an arm D_6 outstanding from the axis of the integrator lantern I_3 which itself in the example shown is constantly urged by a spring (not shown) to turn in a clockwise direction as seen from above. 70

This construction without pivots except those of the integrator frame is one easy to make, free from friction and backlash and kinematically complete. All the elements 75 rest by knife edges or points in notches or conical holes, and each one can be lifted off at any time. The lever system derives its motion from the variation of level of the determining points carried by the two thermometers and these two thermometers each rest by a cone in a conical depression in a rigid metallic structure. 80

As seen in Figure 2, tubes B_{33} B_{34} are soldered to the cold and hot thermometer 85 vessels respectively so as to contain standard mercurial thermometers by means of which the action of the operative thermometers may be checked. These two tubes are carried up through the lid of the calorimeter 90 casing C to a convenient level at which to read the mercury index of each. The upper ends of these tubes are slit longitudinally and sprung inwards so as to hold the thermometers at the desired level. By 95 this means the mercurial thermometers are surrounded by metal at nearly the same temperature as the bulbs, and the errors due to exposed stem are almost entirely eliminated. The tube B_{34} belonging to the hot vessel 100 cannot be seen in the vertical section Figure 1, as it is in front of the plane of section, but B_{33} belonging to the cold vessel is seen partly broken away, as this part is shown in elevation. 105

As will be seen in Figure 2, the conducting shield C_{25} is brought round outside the thermometer tube B_{34} . The shield C_{25} is kept in place by the split ring of willow or other non-conducting material B_{35} which is secured as shown by string or wire. The neck of the hot water vessel which locates it and is strengthened by it, serves to prevent local heat currents from being set up which act as local regenerators. 110

Referring again to the thermometer lever system, it will be seen that either of the screws T_{28} or T_{28a} may be used to bring the pen carried by the lantern, as described in my said former application, to the place 115 on the record sheet corresponding to the temperature of difference shown by the mercurial thermometers, but the screw T_{28} entering the lid and covered by a special cover B_{36} is the more convenient. It will 120 be evident also that the scale of magnification is adjustable by means of the screw D_4 which alters the length of the short arm of the bell crank lever D . Further provision is made for larger variations of scale 125 130

to meet special requirements as a number of conical holes are provided in the arm D_6 which is the short arm of the pen lever and the link D_5 can be made to engage 5 any one of these. It will be evident also that if for any reasons temperatures higher or lower than those intended are developed, no strain is thrown upon the lever system when the pen is prevented from further 10 movement by reason of the engagement of the lantern I_3 with the sides of the integrating drum I_6 for the hot thermometer or the cold thermometer lever will be lifted off its seat and will settle down again when normal 15 temperatures are resumed.

It will be seen from Figure 1 that the integrating wheel I_8 is carried on a pivoted frame J_1 carried on the cantilevers J_2 attached to the lantern I_3 and in part counter-balanced by the weight J_3 . By this 20 means the pressure between the integrating wheel and drum may readily be made definite and small and the weight of the integrating frame is taken by the pivot I_5 resting on the screw J_4 . This construction 25 gives rise to a minimum of friction and interferes in no observable degree with the accuracy of the record.

When the improved construction of inter- 30 changer is used in a non-recording calorimeter the operative thermometers are not required and mercurial thermometers are placed directly in the entering and leaving water, and only narrow water tubes are then 35 required instead of the large vessels required by the operative thermometers.

In order to avoid the considerable fluctuations of temperature which would result 40 if the water passed direct from the surface of the interchanger to the hot thermometer, I make use of the equalizer which I have used in my original gas calorimeter as shown in Figure 4. In this, the upper part 45 of the interchanger is seen in elevation and above it the equalizer in section. This consists of two discs E_1 , E_2 of sheet metal separated from one another and from the interchanger below and the top of the hot water chamber above by open spirals of sheet 50 metal E_3 so that the water in passing through as shown by the arrows, takes spiral routes and interchanges small difference of temperature between successive portions of water by conduction through the metal and in part by leakage if the spirals do not fit 55 accurately. When so used as a non-recording calorimeter there is no necessity to use the water or gas measuring and delivering system as described in said former applica- 60 tion, and, of course, the integrating system and pen recording drum are not required. While this is true the general system as described including the water and gas measuring and delivering devices (but without the 65 means for correcting gas volumes), the

water wheel and one wheel clock may be used with convenience and advantage.

Insulating material is wound round the whole of the hot water vessel C_5 and C_{25} as will be well understood, but this is not 70 shown in the figures to avoid confusion.

I have provided means whereby a source of error not hitherto adequately counteracted may be eliminated, but as the nature of the error is not very commonly understood, I think it desirable to explain it. When gas is burned in air, the volume of the products of combustion when cooled is not equal to that of the gas and air together before combustion, but is less, the exact 75 amount of contraction depending on the composition of the gas. This contraction may give rise to error more or less and positive or negative according to the hygrometric state of the air. If by way of example, 80 the volume of air is seven times that of the gas before combustion and the contraction is one eighth of the whole so that the volume of the gas disappears, then if the air before combustion is six sevenths saturated with 85 water vapour and the gas after leaving the wet meter is saturated, the products being necessarily saturated, the amount of water leaving as vapour will be equal to that entering as vapour, and only in such case the 90 error referred to does not arise.

If, however, as in dry weather, the air is less than six sevenths saturated, then more water leaves the calorimeter as vapour than enters it as vapour, and the heat necessary to convert this amount of water into vapour at the temperature of the effluent gases is abstracted from the calorimeter and to this extent the record is too low. Conversely, if the air is more than six sevenths saturated 95 100 vapour is condensed in consequence of the contraction and generates heat which was not caused by the combustion of the gas, thus making the record too high. Further the higher the temperature at which the cold water enters the calorimeter the greater 105 will be the error positive or negative due to this cause.

So far as I am aware no attempt has been 110 made to correct for this error, but saturation of the incoming air has been employed 115 ensuring too high a result at all times. The whole error due to contraction is never great, but it is persistent. In moist climates like that of England this error is seldom 120 serious, but in dry countries, such for instance, as the east side of America, the negative error may amount to a considerable fraction of one per cent. I provide means for avoiding this error, or at least reducing 125 it to a great extent, which I have illustrated in Figures 1, 2 and 5.

The whole of the air for combustion is led to the combustion space of the calorimeter through the wide flat passage C_{20} 130

under the calorimeter, the air entering said passage through the hole B_2 at the bottom of the cold water compartment. The air can only reach this hole by coming down the 5 passage A seen in plan in Figure 2, the partition which forms this passage extending up to within one or two inches of the lid. Air can only enter the cold water chamber either from the room directly through the 10 narrow passages A_2 or indirectly through a saturating device A_3 and thereafter through the orifice A_4 .

In order to determine the suitable proportions of the air entering directly and indirectly I attach two light valves A_5 and A_6 to a lever A_7 , and I cause the lever to move in consequence of the change of dimensions or weight of a hygrometric substance in such manner that if the air in the cold water 20 compartment is drier than a predetermined quantity the lever shall move so as to obstruct the entry of the air from the room through the passages A_2 and to give more free access to the air coming from the saturator A_3 by the orifice A_4 ; conversely, if the air is moister than the predetermined amount, the movement is in the opposite direction. If the air of the room is already 30 as moist as this or more so, then beyond closing the orifice A_4 by which the saturated air enters nothing more can be done. In the Figures 1 and 2 I have shown as a hygrometric substance a hair A_8 carried up the whole height or nearly so of the cold water compartment, round a pulley A_9 and down again to the lever A_7 . The hair is secured at the other end to a winch A_{10} with milled head A_{11} outside the calorimeter case C so that the position of the valves may be adjusted. A window A_{12} is placed opposite the valves so that their position may be seen.

The operation of the saturator is as follows:—Air can only enter at the end A_{13} along the L-shaped box, the plan of which 45 is shown dotted in Figure 2, and the cross section of which on the line 5—5 of Figure 1 is shown in Figure 5. Into this end of the box the warm water from the calorimeter enters by the pipe C_{27} and travelling along 50 the box leaves by the pipe A_{14} . The cold water from the water wheel H_3 passes by the pipe A_{15} into the other end of the saturator box and it leaves by the same pipe A_{14} by which the warm water leaves. This cold 55 water also passes over the leg A_{17} of the L-shaped box by which the air reaches the orifice A_4 . A water tumbling device such as A_{16} may be included in the length of the box so as to rotate and increase the surface 60 of warm and cold water in contact with the moving air. By this means the air first passes over the warm water where it readily absorbs moisture, then over cold water where it is cooled to the temperature of the water, and superfluous vapour, if any, is condensed 65

and is then free to enter the cold water compartment cooled and saturated to the extent determined by the position of the valves. By this means the air entering the combustion chamber may be kept at any 70 desired degree of saturation which is not less than that of the air of the room.

Any source of heat other than the flame, whether continuous or intermittent, may be measured by means of the recording and integrating calorimeter. Electrically produced heat might be measured or such heat capable of very accurate measurement may be used in the place of the mercurial thermometers for calibrating or adjusting the recording system. The recording and integrating calorimeter may in particular be employed with very great advantage for measuring the heat developed in a calorimetric bomb. For this purpose the interchanger and flame are replaced by the bomb which is carried on a plate which like the ring C_6 can be screwed to the base of the calorimeter. Then the water and clock are started and the instrument is left until the record made by the pen shows that steady conditions have been attained. Then the contents of the bomb are ignited as usual electrically and the instrument is left to itself. After sufficient time for the steady 80 conditions again to be attained the record can be seen and measured. The area enclosed by the heat curve and straight line joining the beginning and end of the disturbance is a measure of the heat developed 85 in the bomb, and this may be read direct on the integrating wheel. For this purpose the integrating drum would advantageously be geared so as to turn more quickly, and the scale of magnification of the pen movements and the flow of water would be chosen 90 to be suitable for the conditions of the experiment.

Having now described my invention, what I claim as new and desire to secure by Letters Patent is:—

1. A recording calorimeter including in combination an operative thermometer formed of a rigid cylindrical vessel provided at each end with a resilient disc, a fixed abutment supporting the centre of one disc and adjustable operative means abutting the centre of the other said disc.

2. The combination in a recording calorimeter of two identical hot and cold operative thermometers, a separate lever operatively connected to each and a third lever co-acting with said first-mentioned levers to operate in the third dimension of space.

3. The combination in a recording calorimeter of two identical hot and cold operative thermometers, a separate lever operatively connected to each and a third lever co-acting with said first-mentioned levers to operate in the third dimension of space,

said third lever incorporating leverage adjustment means.

4. The combination in a recording calorimeter incorporating a drum and disc integrating device of a pivotal lantern framework, supporting means for said framework independent of the integrator drum and a

partly balanced supporting frame for the integrator disc rigid with said lantern framework.

In testimony whereof I have signed my name to this specification.

CHARLES VERNON BOYS.
